[57] CLAIM

The ornamental design for a monitor stand, as shown and described.

DESCRIPTION

FIG. 1 is a front elevational view of a monitor stand showing our new design;

FIG. 2 is a left side elevational view thereof;

FIG. 3 is a right side elevational view thereof;

FIG. 4 is a back elevational view thereof;

FIG. 5 is a top plan view thereof;

FIG. 6 is a right side cross-sectional view thereof;

FIG. 7 is a bottom plan view thereof;

FIG. 8 is a perspective view thereof on a slightly reduced scale.

FIG 1**FIG 2****FIG 3****FIG — 4****FIG — 5****FIG. 6**

FIG 7**FIG. 8**
